UNITED STATES PATENT OFFICE.

ERIC SWENSSON, OF MINNEAPOLIS, MINNESOTA, ASSIGNOR TO MINNEAPOLIS STEEL & MACHINERY COMPANY, OF MINNEAPOLIS, MINNESOTA, A CORPORATION.

REINFORCED STEEL BEAM.

No. 871,075.

Specification of Letters Patent.

Patented Nov. 12, 1907.

Application filed June 17, 1907. Serial No. 379,362.

To all whom it may concern:

Be it known that I, ERIC SWENSSON, a citizen of the United States, residing at Minneapolis, Hennepin county, Minnesota, have invented certain Improvements in Reinforced Steel Beams, of which the following is a specification.

The object of this invention is to provide a steel beam, reinforced by concrete, which two materials in combination make a beam strong enough to carry the entire dead and live loads upon said beam, which is to be an integral part of any structure suitable for this kind of construction. Said combination of two materials, steel and concrete, is intended to provide a maximum of strength together with a minimum of material, with certainty, ease and facility of erection, and also intended to constitute an improved fire proof construction.

To this end the invention consists in the constructions and combinations hereinafter described, and particularly pointed out in the claims.

In the accompanying drawing, forming part of this specification: Figure 1 is an elevation, partly broken away, of a beam embodying my invention and showing in general its arrangement and details. Fig. 2 is a transverse vertical section of the same beam. Fig. 3 is also an elevation of a modified beam embodying my invention. Fig. 4 is a transverse vertical section of the beam shown in Fig. 3.

In carrying out this invention, I provide an I-section formed, preferably, of the upper and lower angle-irons, one pair 1 and one pair 2 laced together by the diagonal bars 3. A single system of these bars may be employed, as shown in Fig. 1 or a double system as shown in Fig. 3. In any case, this web lacing is to be sufficient to provide for any web stresses in the beam, engendered by dead load during construction and erection, and also sufficient in conjunction with the wiring and concrete further on mentioned, to provide for possible web stresses when the beam is in full action under total dead and live loads.

I make the steel section at the top of the beam much smaller than the steel section at the bottom of the beam, because the concrete will resist most of the compression at the top, while the concrete, being weak in tension, cannot resist the tension at the bottom of the beam, which tension therefore has to be resisted almost entirely by the steel reinforcement. To provide this difference between the sectional area of the steel at the top of the beam, and the sectional area of the steel at the bottom of the beam I can make the sectional area of the angle-irons at the bottom of the beam larger than the sectional area of the angle-irons at the top of the beam. But a better construction admitting of closer

adherence to requirements found by theoretical investigations, and in general admitting of greater variation 55 and ease of construction, is to insert at the bottom of the beam, in addition to the angles 2 of the same sectional area as the angles 1, the rods 4. These rods 4, besides giving facilities for obtaining the exact cross sectional area of the steel required at the bottom of the 60 beam, also admit of increased economy, because by varying the lengths of these rods I can provide a steel section at the bottom of the beam more closely corresponding to the requirements of the pending moment under which the beam is acting, than otherwise would 65 be possible. These rods 4, preferably will be bent up at ends and fastened rigidly to the lower angle-irons.

Outside the I-section and at a small distance from the face of the concrete, as shown in Figs. 2 and 4, I provide a strong steel wiring 5. This wiring is wound 70 the whole length of the beam with either a constant or a varying pitch. This wiring to be held in place to its proper pitch by suitably arranged longitudinal spacing bars, rods or wires 6. The purpose of this wiring is to increase the compressive resistance of the 75 concrete, and to prevent the concrete from disintegrating or flaking off the steel during stress. My experiments have shown that if this wiring is rightly proportioned, as to size and pitch, the concrete will adhere to the steel and take its proper share of the 80 stresses engendered by the loads under which the beam is acting, even when these loads will rupture the steel framing. This the concrete otherwise will not do. But also, in addition to thus greatly increasing the strength of the beam this wiring also greatly 85 increases the fireproof qualities of the construction, because even under most severe fire the concrete will crack off only until the wiring is reached and no further, thus leaving the strength of the beam nearly unimpaired. In fact, this wired concrete will have 90 the same fire resistance relative to the plain concrete as wire glass has to plain glass.

Thus it is to be clearly understood that this reinforced steel construction of beams here shown and described has for its object not only the use of concrete as a necessary fireproofing, but also its use as a large and important factor contributing to the carrying capacity of the beam, the wiring greatly augmenting the strength of the concrete; said wiring also making the concrete act conjointly and harmoniously 100 with the steel framing, thus enabling me to attain the same simultaneous factor of safety in both materials, all which full size tests made by me has shown to be true.

I do not limit myself to the details of the construction, as these may be varied in many particulars with-

out departing from my invention, the accompanying drawings, together with above description being intended to show only fundamental essentials.

I claim as my invention:

5 1. A reinforced steel beam comprising, in combination, an I-section formed of upper and lower angle-irons laced together, a steel wiring surrounding said I-section, and a concrete filling, substantially as described.

10 2. A reinforced steel beam comprising, in combination, an I-section formed of upper and lower angle-irons laced together, a steel wiring of varying pitch surrounding said I-section, and a concrete filling, substantially as described.

15 3. A reinforced steel beam comprising, in combination, an I-section formed of upper and lower angle-irons laced together, and steel wiring surrounding said I-section, said steel wiring being held to its proper pitch and place by longitudinal spacing bars, rods or wires, and a concrete filling, substantially as described.

20 4. A reinforced steel beam comprising in combination an I-section formed of upper and lower angle-irons laced together, the angle-irons at the top of the beam being smaller than those at the bottom of the beam, a steel wiring surrounding said I-section and a concrete filling, substantially as described.

25 5. A reinforced steel beam comprising, in combination, an I-section formed of upper and lower angle-irons laced together, the angle-irons at the top of the beam being smaller than those at the bottom of the beam, a steel

wiring surrounding said I-section said steel wiring being held to its proper pitch and place by longitudinal spacing bars, rods, or wires, and a concrete filling, substantially as described.

6. A reinforced steel beam comprising in combination an I-section formed of upper and lower angle-irons laced together, a system of rods parallel to and near to the lower angle-irons, a steel wiring surrounding said I-section, said wiring being held in place by longitudinal spacing bars, rods, or wires, and a concrete filling, substantially as described.

7. A reinforced steel beam comprising, in combination, an I-section formed of upper and lower angle-irons, one pair above, one pair below, diagonal lacing straps connecting said pairs of angle-irons, a system of rods parallel to and near to the lower angle-irons, said rods being of different lengths as required by the bending moment under which the beam is calculated to act, said rods also being rigidly fastened to the lower angle-irons, a steel wiring surrounding said I-section and said rods, said steel wiring being held to its proper pitch and place by longitudinal spacing bars, rods, or wires, and a concrete filling, substantially as described.

In witness whereof, I have hereunto set my hand this 7th day of June 1907.

ERIC SWENSSON.
